United States Patent Office

Des. 218,858
Patented Sept. 29, 1970

218,858

AIRCRAFT

Walter E. Fellers, Los Angeles, Ronald M. Beattie, Camarillo, and Michael G. Huben and Don M. Heinze, Los Angeles, Calif., assignors to Northrop Corporation, Beverly Hills, Calif., a corporation of California

Filed June 30, 1969, Ser. No. 17,976

Term of patent 14 years

Int. Cl. D12—07

U.S. Cl. D71—1

FIG. 1 is a perspective view viewed from above of the aircraft employing our design.

FIG. 2 is a top plan view thereof;

FIG. 3 is a side elevational view thereof, the opposite side being identical; and

FIG. 4 is a front elevational view thereof.

We claim:

The ornamental design of an aircraft, substantially as shown and described.
